UNITED STATES PATENT OFFICE.

FRED W. SWAIN, OF NORTH CHELMSFORD, MASSACHUSETTS, ASSIGNOR TO C. G. SARGENT'S SONS CORPORATION, OF GRANITEVILLE, MASSACHUSETTS, A CORPORATION OF MASSACHUSETTS.

RAKE-OPERATING DEVICE FOR WOOL-WASHING MACHINES.

1,164,888.

Specification of Letters Patent. Patented Dec. 21, 1915.

Application filed May 12, 1915. Serial No. 27,669.

To all whom it may concern:

Be it known that I, FRED W. SWAIN, a citizen of the United States, residing at North Chelmsford, in the county of Middlesex and State of Massachusetts, have invented a new and useful Rake-Operating Device for Wool-Washing Machines, of which the following is a specification.

This invention relates to an operating means for the rake of a wool washing bowl.

The principal objects of the invention are to provide for this purpose mechanism which shall be simpler than the ordinary rake operating mechanisms now in use, which can be adjusted to vary the kind of motion of the rake so as to make it circular or elliptical as may be desired, and in which this controlling mechanism can be located entirely above the top of the bowl; and also to provide an improved device for introducing the liquor into the rear end of the bowl and varying its rate of entrance.

Reference is to be had to the accompanying drawings, in which—

Figure 1 is a side elevation of a wool washing machine constructed in accordance with this invention; Fig. 2 is a similar view with the operating and similar parts in sectional view on a central longitudinal plane, and with the parts in a different position; Fig. 3 is a sectional view on the line 3—3 of Fig. 1; Fig. 4 is a sectional view of the eccentric on enlarged scale showing it in another position; and Fig. 5 an inside end view of the means by which the liquor is introduced into the bowl.

The invention is shown in a form in which it is applied to an ordinary rake but it is understood that it can also be applied to rakes having claw teeth and other types of wool washing bowls and rakes.

In the form shown, the bowl 10 is provided with the usual screen 11 which extends upwardly at the rear at the point 12, the rear portion being spaced from the rear end of the bowl. The washing liquor is introduced into the bowl at its end through a pipe 13 which discharges into a chamber 14 located on and constituting a part of the end of the bowl. The passage of the liquor from this chamber into the bowl is regulated by a plate 15 which is provided with a row of perforations 16 near the top. This plate is held in position by bolts and can be ad-

justed up and down to a certain extent. It will be understood that as the plate is adjusted upwardly a portion of each perforation 16 is cut off by the top wall of the chamber 14 and thus the amount of liquor entering the bowl is regulated. It will be seen further that these perforations are about on the level, or a little above the top, of the end 12 of the screen. This permits the liquor to be discharged inwardly over the top of this projection and lets the liquor from the bottom pass upwardly behind it and over its top as indicated by the arrows in Fig. 1.

A rake 20 of ordinary construction is shown supported by uprights 21 on the top of the bowl. These uprights as usual are provided with shafts 22 on which are weighted arms 23 from which depend links 24 to which the rake is pivotally connected. These arms 23 are connected in the usual way by a longitudinal rod 25 so that a parallel motion is provided for the purpose of raising and lowering the rear end of the rake in accordance with the motion of the front end.

For the purpose of moving the rake longitudinally the following mechanism is provided: Power is transmitted through a wheel 26 to a shaft 27 which is supported by the forward uprights and extends across the machine. On this shaft is an eccentric 28 provided with a strap 29. On this strap is a surface 30 for supporting a roller 31. It will be noted that this surface is provided with two depressions 32 at its sides and when the rake is in either extreme position, the roller 31 will rest in one of these depressions, thus allowing the rake to dip slightly at each extreme of its motion. This roller 31 is carried on a shaft 33 which is provided with a pair of yokes 34. These extend downwardly and are pivoted by means of rods 35 to the forward end of the rake so that the motion of the eccentric not only raises and lowers the front end of the rake, but also moves it longitudinally. In other words, a circular motion is normally transmitted to the forward end of the rake.

The eccentric strap is connected by a rod 36 with the depending rods 24 at the rear of the rake. This connection is made through a transverse rod 37 having a pair of connections 38 thereon adapted to be se-

cured to the links 24 by set screws 39 or the like. Obviously the set screws can be loosened and the connections 38 raised or lowered along the links 24. This turns 5 the rod 36 on the eccentric as a center and permits of variation of the motion of the rear end of the rake and consequently of the entire rake. If the rod is connected as indicated in Fig. 2 the motion is an elliptical one but if it is lowered the to-and-fro motion of the rake at the rear will be decreased and thus a circular motion can be secured, because the rise and fall is not varied by this adjustment. It will be seen, therefore, 10 that this arrangement is simple and compact, can be arranged entirely above the bowl if desired, can be adjusted in an extremely simple way to vary the motion, and is inexpensive.

20 Although I have illustrated and described only a single embodiment of the invention, I am aware of the fact that modifications can be made therein by any person skilled in the art and that it can be applied to other types 25 of wool washing machines without departing from the scope of the invention as expressed in the claims. Therefore, I do not wish to be limited in these respects, but

What I do claim is:—

- 30 1. In a wool washing machine, the combination with a bowl and a rake therefor, of an operating mechanism for the rake comprising an eccentric, a strap for the eccentric, a yoke supported by said eccentric 35 and depending therefrom to support that end of the rake, a rod fixed to said strap and extending toward the other end of the rake, and means for connecting said rod with said other end of the rake to transmit 40 the to-and-fro motion to the rake.
2. In a wool washing machine, the combination with a bowl and a rake therefor, of an operating mechanism for the rake comprising an eccentric, a strap for the eccentric 45 near one end of the rake, a rod rigidly connected with said strap and extending toward the other end of the rake, and vertically adjustable means for connecting the end of said rod with the other 50 end of the rake to transmit the to-and-fro motion to the rake, and adjust the strap angularly about the eccentric.
3. In a wool washing machine, the combination with a bowl and a rake, of a trans-

verse shaft, an eccentric thereon, an eccentric strap for said eccentric, and means mounted over the eccentric strap for moving the rake up and down, said eccentric strap having a cam surface thereon for supporting said moving means whereby the 60 vertical motion transmitted to the rake is varied by the cam at different points in its longitudinal motion.

4. In a wool washing machine, the combination with a bowl and a rake therefor, 65 of an operating mechanism for the rake comprising an eccentric, a strap on the eccentric, means directly pivoted to the rake and operated by the strap for raising and lowering the rake uniformly at both ends, 70 comprising parallel links at the ends of the rake, a rod rigidly connected with said strap and extending toward the other end of the rake, and means for connecting the end of said rod with one of said links at the 75 other end of the rake, said connecting means being adjustable up and down throughout the length of the link, whereby the motion transmitted to the said other end of the rake can be varied.

5. In a wool washing machine, the combination with a bowl and a rake, of a shaft located above the rake, an eccentric thereon, an eccentric strap, circumferentially adjustable means for preventing the eccentric strap 85 from turning with the eccentric, a roll mounted on the top of the eccentric strap, and a yoke connected with said roll and supporting the end of the rake, said eccentric strap having a cam surface on the top thereof having different portions on which the roll can bear.

6. In a wool washing machine, the combination with a bowl, a screen, and a rake, 95 of an inlet pipe for the washing liquor located at the rear end of the bowl, a chamber beyond the rear end of the bowl into which said pipe discharges, a plate located between the chamber and the interior of the bowl having a plurality of perforations 100 therethrough and adjustable up and down to control the rate of discharge into the bowl, said screen extending upwardly and rearwardly substantially to the level of said openings.

In testimony whereof I have hereunto set my hand.

FRED W. SWAIN.
